ANDREW A. ANDRAKE, OF CLEVELAND, OHIO, ASSIGNOR TO THE GLENN L. MARTIN COMPANY, OF CLEVELAND, OHIO, A CORPORATION OF OHIO

LUBRICATION SYSTEM

Application filed August 31, 1927. Serial No. 216,560.

This invention relates to improvements in lubricating systems for internal combustion engines used for the propulsion of aircraft.

The quiet, efficient and satisfactory running of an internal combustion engine is dependent, amongst other things, upon lubrication. The physical characteristics of lubricating oil change greatly with temperature, and no engine can be designed to have maximum efficiency and smooth running under all of the various conditions which may be encountered, it follows that at various times there must be inefficiency and lack of smooth running unless corrective means are provided.

The object of my invention is to overcome the difficulty above mentioned by the provision of means for controlling oil temperature in such a way that the oil in an engine may be brought up to the proper temperature quickly at the time of starting the engine, and may be maintained substantially at a temperature best adapted to conditions encountered at different altitudes throughout any running period.

Another object is the provision of means under control of the operator from his usual position in the aircraft for regulating the temperature of the oil.

Another object is the provision of a radiator in a system of this character for cooling the oil which is circulating therethrough together with manual means for short circuiting the radiator, and also means for regulating the effectiveness of the radiator by manually varying the flow of air therethrough.

Another object is to cushion the pressure of oil in an engine oil circulating system to thus relieve the radiator tubes of abruptly changing pressures due to sudden acceleration of the pump, or to pulsations of the pump, or to excessive stresses caused by abnormally high viscosity of the oil.

Another object is the provision of means for passing heated air through the radiator and through tubes surrounding oil pipes in the system, whereby the raising of the oil temperature may be accomplished before starting the engine.

Another object is to provide means for

simultaneous closure of an air inlet and of an air outlet of a radiator to thus maintain fluidity of the oil contained therein under low temperature conditions, and to facilitate efficient pre-heating of the oil.

Other objects and features of novelty will appear as I proceed with the description of that embodiment of the invention which, for the purposes of the present application, I have illustrated in the accompanying drawing, in which

Fig. 1 is a view in perspective, largely diagrammatic in character, illustrating a part of the lubricating system of an internal combustion engine located outside of the engine casing;

Fig. 2 is a perspective view of a heater which may be employed in carrying out certain features of the invention, and

Fig. 3 is a plan view of a pair of shutter doors which I may employ for regulating the effectiveness of the radiator.

Similar reference characters refer to like parts throughout the views.

In the drawing a fragment of a crank case of an internal combustion engine is illustrated at 10, while the casing of an oil circulating pump is shown at 11 connected with the bottom of the crank case. The present invention is not concerned with the details of the oil pump, which may be of any suitable design so long as it is adapted to take oil from the engine, pass it through a circulating system outside of the engine and then return it to the engine for re-use. By means of such pump the oil that has been heated by use in the engine is caused to leave the same through a pipe 12 and travel into the top of a storage tank 13 which is located upon the aircraft at a point above the level of pump 11. From the bottom of tank 13 a pipe 14 leads downwardly to a radiator 15 which I prefer to form somewhat elongated in a horizontal direction and to mount upon the vehicle with its long dimension parallel to the direction of movement of the vehicle. In effect, the radiator consists of an outer shell and a large number of tubular elements forming air passages within the shell, the spaces between the tubes being closed and soldered

up at each end only. Shrouds 16 and 17 enclose the ends of the radiator, these shrouds being tapered somewhat so that the entire unit comprising radiator and shrouds approximates more or less closely a streamlined body.

At their free ends the shrouds 16 and 17 have circular openings 18 and 19, in each of which I mount a pair of semi-circular shutter doors 20 and 21, respectively, hinged together along their adjacent edges, these doors being provided with intermeshing pinions 9. Both doors of each pair swing backwardly to open. Levers 22 and 23 are attached to one door of each pair and these handles are connected together for simultaneous operation by a rod 24. At the bottom of the shrouds 16, just in front of the radiator, I provide an opening through which may be inserted a heater comprising a cup 25 adapted to contain fuel, preferably in the form of paste, for example, the so-called "solid alcohol" which is procurable in small cans to fit within the cup 25. Over the top of the latter I may mount a wire gauze 26 for confining the flame. A suitable bracket 27 is attached to the shroud 16 for removably supporting the cup 25.

The pipe 14 passes through the top of the shell of the radiator 15 near the rear end of the latter so as to deliver oil by gravity from the tank 13 to the interior of the radiator. Outside the radiator the pipe 14 is connected by a union 28 with a pipe 29 running parallel to the radiator and having connection at its forward end through a union 30 with a pipe 31, the lower end of which extends into the radiator and the upper end of which is connected with the pump casing 11. The valve casing 32 is interposed between portions of pipe 29 and contains a shut-off valve which may be opened or closed by the rotation of a stem 33. A shaft 34 provided with a handle 35 located within the reach of the operator when occupying his normal position is employed for rotating stem 33 through the intermediacy of bevel pinions 36. Means are also provided for moving the rod 24 from a position convenient to the operator. As shown herein this is accomplished by a crank 37 mounted on the lower end of a rock shaft 38 and pivotally connected with the rod 24. The upper end of shaft 38 is provided with an operating handle 39 which may have a pointer thereon movable over the face of a dial 40 provided with markings to indicate the various adjustments of the shutter doors 20 and 21.

A casing 41, which is roughly semi-cylindrical in shape, encloses pipe 29. This casing extends somewhat beyond the ends of the radiator 15 and has a flanged lower edge which is attached to the radiator and to the shrouds 16 and 17. Openings 42 and 43 through the shrouds 16 and 17, respectively,

serve to connect the spaces within the shrouds to the space within the casing 41. This casing merges into tubes 44 and 45 surrounding the pipes 14 and 31, respectively, these pipes being open at their upper ends.

In the drawing the flow of oil is indicated by solid line arrows, while the flow of air is indicated by broken line arrows.

Operation.—When an engine equipped with my invention is to be started, the fuel in cup 25 is ignited and the cup is mounted in bracket 27. The shutter doors 20 and 21 are closed, or substantially closed. The air within the shroud 16 is thereby heated. Some of it moves through the air spaces in radiator 15, which contains engine oil, and thence through opening 43 into casing 41 and out through one or both of the tubes 44 or 45. Some of the heated air also passes through opening 42 directly into casing 41 and thence through tubes 44 and 45. In either event, heat is transferred from the air to the oil either through the walls of the radiator tubes or through the walls of pipes 14 and 31. The size of hole 42 may be varied to control the proportion of heated air that shall pass through that opening and through the radiator tubes, and, if desired, the hole 42 may be omitted entirely so that all of the heated air must traverse the radiator.

The heater 25 may be caused to function for a time before the engine is started with the result that a considerable quantity of oil, that is, all that is contained within the radiator 15, is rendered warm and fluid, while that contained within the pipes 14 and 31 is also heated to a greater or lesser extent. Consequently from the moment the engine is started it is supplied with warm oil, and the usual difficulty in starting, in so far as it is caused by cold lubricant, is avoided. As further oil flows into the radiator to take the place of that drawn into the engine, this oil is also heated, and thus in a short time a considerable part of the oil in the system has been brought up to a temperature which approximates the most desirable running temperature.

Usually before the aircraft starts from its position of rest the fuel in heater 25 will be exhausted or the heater removed. During normal running the oil extracts from the engine more heat than is necessary to keep it at the most desirable temperature. After the aircraft has been in motion for a time the oil temperature may rise above the maximum which is considered desirable. The pilot then moves handle 39 to open shutter doors 20 and 21, more or less, thereby permitting the motion of the aircraft to draw cool air through the radiator 15, by which means some of the heat is absorbed from the oil. On the other hand, should low temperature conditions be encountered, as where an aircraft rises to a great height, and the oil conse-

quently should become too cool for satisfactory operation even with the shutters 20, 21 fully closed, the operator may then turn handle 35 to open the valve in the by-pass pipe 5 29 whereupon the oil is free to move directly from pipe 14 to pipe 31 without passing through the radiator 15, and thus very little of the heat absorbed by the oil from the engine is lost in the circulating system outside 10 the engine, with the result that the temperature of the whole body of oil in the system gradually rises. Hence it will be observed that the use of my invention enables the operator to adjust the oil temperature in accordance 15 with atmosphere temperature and altitude conditions as visually indicated to him by his instruments and as his judgment dictates.

While I have described the invention with 20 more or less particularity and have shown the same somewhat in detail in the appended drawing, it should be understood that such detail disclosure is employed for purposes of illustration and is not to be construed as 25 limiting the invention except where such details are specifically included within the appended claims.

Having thus described my invention, I claim:

30 1. In a lubricating system for vehicle engines, an oil pipe in said system located outside of the engine, a tube enclosing a portion of said pipe, one end of said tube being higher than the other, a substantially closable 35 chamber at the lower end of the tube, and a detachable heating unit having an opening therethru located in said chamber.

2. In a lubricating system for aircraft engines, means for regulating the temperature 40 of engine oil comprising a radiator and by-pass combination unit having an inlet and an outlet; a reserve oil pressure supply tank outside said engine cooperating with said radiator unit to cool said oil; manually operable means associated with said unit for proportioning flow of oil through the by-pass of 45 said unit to thereby affect the rate of oil flow through said radiator; means operated by the engine for delivering oil from said engine to 50 said tank; a gravity flow pipe from said tank to said radiator and by-pass unit inlet, and a return flow pipe from said radiator and by-pass unit outlet to said pump.

3. In an aircraft engine lubricating system, 55 a longitudinally disposed oil cooling radiator comprising in combination a streamlined shell; passages within said shell for air and for oil; means for connecting said oil passages to said system; two shutters, one at 60 each end of said shell and means under control of an operator for simultaneous operation of said shutters.

4. In an aircraft engine lubricating system, 65 a longitudinally disposed oil cooling radiator comprising in combination a stream-

lined shell; passages within said shell for air and for oil; means for connecting said oil passages to said system; a bifurcated shutter, the half portions of said shutter geared together for simultaneous movement in one direction, and means under control of an operator for operation of said shutter.

5. In an aircraft engine lubricating system, 70 a longitudinally disposed oil cooling radiator comprising in combination a streamlined shell; passages within said shell for air and for oil; means for connecting said oil passages to said system; two bifurcated shutters, one at each end of said shell, the half portions of each of said shutters geared together for simultaneous movement in one direction, one of said shutters opening inwardly toward said passages and the other of said shutters opening outwardly of said 75 passages; and means under control of an operator for simultaneous operation of said shutters.

6. In a lubricating system for aircraft engines, means for circulating engine oil outside the engine, said means including a radiator mounted upon the aircraft in longitudinal relation, said radiator comprising a tubular shell, air passages and oil passages longitudinally disposed within said shell, and manually operable shutters for the inlet and 90 the outlet of said air passages; a by-pass in said circulating means around said radiator; a valve in said by-pass; and means in proximity to the operator's seat for operating said valve and said shutters for controlling the relative 95 flow of oil and air through said radiator.

In testimony whereof, I hereunto affix my signature.

ANDREW A. ANDRAKE.
